MOLDING TOY

Gale D. Jenkins, Jr., Cincinnati, Ohio, assignor to Rainbow Crafts, Inc., a corporation of Delaware

Filed Apr. 21, 1969, Ser. No. 16,832

Term of patent 14 years

Int. Cl. D21—02

U.S. Cl. D34—15

FIG.-1

FIG.-2

FIG.-3

FIG. - 6

FIG. - 4

FIG. - 5

FIG.-7

FIG.-8

FIG. 1 is a perspective view of a molding toy with the cover closed illustrating my new design;

FIG. 2 is a side view of the molding toy illustrated in FIG. 1;

FIG. 3 is a top plan view of the molding toy illustrated in FIG. 1;

FIG. 4 is an end view of the molding toy illustrated in FIG. 1;

FIG. 5 is a front view of the molding toy illustrated in FIG. 1;

FIG. 6 is a top view of the molding toy with the cover open illustrating my new design;

FIG. 7 is a perspective view of the molding toy with the cover open; and

FIG. 8 is a bottom view of the molding toy illustrated in FIG. 1.

I claim:

The ornamental design for a molding toy, substantially as shown.
